UNITED STATES PATENT OFFICE

ELLIS G. MALPAS, OF MUSKEGON, MICHIGAN, ASSIGNOR TO THE PISTON RING COMPANY, OF MUSKEGON, MICHIGAN, A CORPORATION OF MICHIGAN

PISTON RING

Application filed May 25, 1931. Serial No. 539,716.

This invention relates to piston rings.

It is common in piston rings to provide the same with either a continuous groove, or with a series of grooves or chambers spaced a very short distance and separated by narrow bridges from each other at their ends around the ring. In either case at the parting in the ring, the ends of the ring are grooved leaving very thin or narrow outstanding lips or flanges which, at the extreme ends of the ring at the parting, are to a large extent unsupported and are very liable to chip off or otherwise become broken in assembling or in service in an engine. The braking of small particles of iron from the thin outwardly extending flanges above and below the grooved parting ends of the rings is very undesirable, both from the standpoint of loss of efficiency in the ring, from possible scoring of cylinders, or the eventually carrying of the chipped or broken particles of iron to the crank case of the engine where the same mingle with the oil and may be carried or splashed to bearings with a resultant detriment thereto.

The present invention has for its object and purpose the construction of a piston ring for obviating such weakening of the flanges produced by deeply grooving the ring to its ends at the parting thereby providing a construction wherein the flanges are made very much less in depth with consequent insurance against breaking or chipping of the same.

The invention may be understood from the following description, taken in connection with the accompanying drawing, in which.

Fig. 1 is a plan view illustrating a grooved ring equipped with my invention.

Fig. 2 is a fragmentary enlarged plan view of the parting ends of a ring, with parts thereof shown in section to better illustrate the invention.

Fig. 3 is a fragmentary elevation of the two portions of the ring, one at each side of the parting, as shown in Fig. 2, and

Fig. 4 is a view similar to Fig. 3 showing the invention applied to a ring in which the groove around the outer side of the same is not continuous but comprises a series of

grooves around the ring which are separated from each other at their ends short distances.

Like reference characters refer to like parts in the different figures of the drawing.

The ring 1 is a single piece ring having a parting 2 at one side as is usual in piston rings; and in the form of ring shown in Figs. 1 to 3 inclusive, a continuous groove 3 is cut in the outer curved side of the ring, and from the bottom of this groove at spaced apart intervals drainage slots 4 for oil are sawed through to the inner curved side of the ring, the ends of said slots being separated by intervening posts 5 integral with the body of the ring.

It is evident that with the groove 3 continued its full depth to the ends of the ring at the parting, the upper and lower flanges which are left above and below the groove are thin, particularly in the narrow width rings almost universally used in internal combustion engines, said flanges being unsupported at their free ends; and the same are very prone to chip off, crystallize and break or otherwise become disrupted.

In my invention in the form of the ring shown in Figs. 1 to 3 inclusive the ends of the groove 3 adjacent each end of the ring, at the parting 2, are not continued the full depth of the groove, but terminate a short distance from each end of the ring at the parting and outwardly extending humps or bosses 6 at each side of the parting in the groove 3 are left providing much shallower grooves 7 between the outer sides of said bosses 6 and the outer edges of the flanges which are left when the groove is cut. The flanges at each side of the much shallower short groove portions 7 in this manner are

not weakened to any detrimental extent and do not crystallize or otherwise break or shatter in assembly or in service, while at the same time the collection of oil at the parting of the ring in the groove around the ring is not diminished to any detrimental degree.

The invention is applicable to other types of rings than rings having a continuous groove. For instance, as shown in Fig. 4, the ring 1a having a parting 2a, is not grooved

continuously around its entire outer surface but sections or lengths of grooves 8 are made in the outer surface of the ring, separated at their adjacent ends by intervening narrow spaced sections or bridges 9 which form part of the outer curved side of the ring. Drainage slots 10 are cut from the bottoms of the groove sections 8 through to the interior of the ring.

At the parting in the ring, however, at each side thereof, a like boss or hump 6a is left in the ring so as to provide a shallow rather than a deep groove cut at the parting, for when the groove is deep as has been heretofore made, it leaves narrow relatively deep and comparatively fragile flange ends subject to breaking, crystallizing and the like.

The type of ring shown in Fig. 4, to which my invention is shown applied is like that illustrated in my pending application Ser. No. 482,390, filed September 17th, 1930, and in the present application, I have applied thereto the integral raised reinforcing bosses 6a at the parting for the purposes which have been described and set forth. This invention is very practical and serviceable and of value in connection with piston rings which are grooved across the parting ends thereof.

The invention is defined in the appended claims and is to be considered comprehensive of all forms of structure coming within their scope.

I claim:

1. A piston ring of substantially circular form, having a parting at one side and grooved between its parallel flat sides and at its outer surface at and for a distance to each side of the parting, said groove directly at and a short distance to each side of the parting being shallow and then deeper, there being integral outwardly projecting portions of the piston ring at each side of said parting providing the bottom of the shallow portions of the groove and ends of the adjacent deeper portions thereof.

2. A piston ring having, a parting in a side thereof and formed with a series of consecutive groove sections around the ring away from said parting, the adjacent ends of said groove sections running out to the outer curved surface of the ring and being spaced from each other by short lengths of said outer surface of the ring, and bosses integral with the ring at each side of the parting projecting into the adjacent groove sections to within a short distance of the outer surface of the ring, as specified.

3. A construction containing the elements in combination defined in claim 2 combined with passages extending through the ring from the bottoms of said groove sections to the inner surface of the ring.

In testimony whereof I affix my signature.
ELLIS G. MALPAS.
